AUTOMOBILE TAIL LAMP

Donald J. Reid, Saginaw, Mich., assignor to Chrysler Corporation, Highland Park, Mich., a corporation of Delaware

Application July 15, 1954, Serial No. 31,438

Term of patent 7 years

(Cl. D48—32)

To all whom it may concern:

Be it known that I, Donald J. Reid, a citizen of the United States, residing in the city of Saginaw, county of Saginaw, and State of Michigan, have invented a new, original, and ornamental Design for an Automobile Tail Lamp, of which the following is a specification, reference being had to the accompanying drawing, forming part thereof, in which:

Fig. 1 is a front elevational view of an automobile tail lamp, showing my new design;

Fig. 2 is a side elevational view thereof; and

Fig. 3 is a top plan view thereof.

I claim:

The ornamental design for an automobile tail lamp, substantially as shown.
